UNITED STATES PATENT OFFICE

DON HEYER, OF LOS ANGELES, CALIFORNIA

DESIGN FOR A FRAME FOR A POWER UNIT

Application filed October 28, 1932. Serial No. 45,611. Term of patent 7 years.

To all whom it may concern:

Be it known that I, DON HEYER, a citizen of the United States, and a resident of the city of Los Angeles, in the county of Los Angeles and State of California, have invented a new, original, and ornamental Design for a Frame for a Power Unit, of which the following is a specification, reference being had to the accompanying drawings, forming part thereof, in which—

Figure 1 is a top plan view of the frame showing my new design;

Fig. 2 is an end view thereof;

Fig. 3 is an end view from the other side of the frame; and

Fig. 4 is a side view of the frame.

I claim:

The ornamental design for a frame for a power unit, substantially as shown.

DON HEYER.
